CALLING DEVICE

Fredric E. Wood, McHenry, Fred Gienger, Highland Park, Erik Decker, Chicago, and Robert L. Sargisson, Berwyn, Ill., assignors to Automatic Electric Laboratories, Inc., Chicago, Ill., a corporation of Delaware

Application October 30, 1946, Serial No. 706,608

5 Claims. (Cl. 179—90)

1

The present invention relates to calling devices of the impulse transmitting type and more particularly to improvements in calling devices of the character disclosed in U. S. Patent No. 1,642,822, Herbert F. Obergfell, granted September 20, 1927.

The calling device disclosed in the Obergfell patent mentioned comprises, among other elements, a substantially cup-shaped casing carrying certain other parts including lugs, tabs and brackets on the bottom thereof, to which other elements, including a set of impulse spring contacts, a set of cam spring contacts, a speed governor, etc., are secured in position below the casing. This cup-shaped casing supports other various mechanisms of the device, including the usual finger hold dial, the usual number plate, and the ratchet and pawl mechanism for controlling the impulse spring contacts through suitable gearing. The finger hole dial and the ratchet and pawl mechanism are rotatably mounted in a hub which is staked to the cup-shaped casing.

While the construction of this calling device is entirely satisfactory in service and exceedingly strong and durable, it was more expensive to manufacture and required considerable time to assemble. Accordingly, a latter improvement used an improved die-cast casing of zinc base alloy to replace the cup-shaped casing, which included all necessary openings, lugs, tabs and brackets formed integrally therewith during the die-casting operation in order to eliminate certain machine operations required to assemble the device. At first the hub was staked to the cast cup-shaped casing in the same manner as shown in the Obergfell patent but this was found to be entirely unsatisfactory because the casing, being made of a zinc base alloy was too soft and often resulted in breakage and loosening of the hub after the calling devices were put into use.

Accordingly, it is the object of the present invention to provide an improved calling device which is of simple and rugged construction, which may be readily assembled in a minimum amount of time, which is inexpensive to manufacture, and which is durable.

Another object of the invention is to provide a calling device of the type noted comprising an improved die-cast casing having the necessary lugs, tabs, brackets and openings formed integrally therewith during the die-casting operation in combination with an improved ring-staked clamping arrangement whereby the soft-die cast casing is rigidly held between two hard

2

metal pieces, namely the driving spring tension plate and the number plate spring; the number plate spring being assembled on one side of the casing, the driving spring tension plate being assembled on the other side of the casing, the hub being inserted through holes in the number plate spring, and the casing, and forced-fit through a shoulder of the driving spring tension plate after which the hub is ring-staked to the driving spring tension plate to securely and rigidly clamp such members together. This method of clamping the soft casting of the cup-shaped casing between these two members overcomes the breakage trouble of the die-cast casing and the loosening of the hub as previously mentioned.

The invention is illustrated in the accompanying drawings comprising Figs. 1 to 6, inclusive, wherein:

20 Fig. 1 is a front view, partly broken away, of a calling device embodying the present invention,

Fig. 2 is a rear view of the calling device shown in Fig. 1,

Fig. 3 is a cross section taken on line A—A of Fig. 4,

Fig. 4 is a top view of the casing with certain parts removed,

Fig. 5 is an enlarged cross section view showing the method of assembling the hub, casing, number plate spring and the driving spring tension plate,

Fig. 6 is a cross section of the hub before the ring-staking operation.

Referring now more particularly to Figs. 1 to 4, inclusive, of the drawings, the calling device 10 shown is of the finger wheel controlled impulse transmitting type and of the general construction and arrangement of the calling device disclosed in the previously mentioned Obergfell patent. The calling device 10 comprises a substantially cup-shaped casing 11 which is formed by a conventional die-casting operation of a relatively soft zinc base alloy, a number plate 12 secured in the open end of casing 11 by the curved ends 28 and 29 of the number plate spring 27 and mechanism, not shown, housed within the casing 11. The mechanism housed in the casing 11 is similar to that shown in the previously mentioned Obergfell patent and comprises a rotatably mounted operating shaft, not shown, the upper end of which carries a rotatable finger wheel or dial 13 overlying the number plate 12. A depression is formed in the central portion of the finger wheel 13 in which an escutcheon plate 15 is removably secured. A finger stop 16 is secured to

the bottom of casing 11 by an arrangement comprising two aligning pins 18 fixed to the base and projecting through openings in the casing 11 and by two screws 19 extending through openings in casing 11 and which are secured by the nuts 20 resting in counter depressions in casing 11. This arrangement of the aligning pins 18, the screws 19 and the nuts 20 is necessitated in view of the fact that the zinc base alloy of casing 11 is so soft that it is not desirable that it be threaded to receive directly the threaded ends of screws 19.

The mechanism housed in casing 11 comprises, in addition to the operating shaft previously mentioned, an impulsing shaft 21 and one-way drive mechanism between the operating and impulsing shafts. The inner ends of these shafts project through openings provided in the casing 11. A fixture 33 is secured to the end of the operating shaft for operating the shunt and impulsing contact springs and a cam 34 is secured to the impulsing shaft in a manner similar to that shown in the Obergfell patent. A driving spring, one end of which is shown at 25, Fig. 2, surrounds the operating shaft and extends between the fixture 33 and the driving spring tension plate 24 which has lugs, such as lug 26, for holding one end of the driving spring. A section of the impulsing shaft extends through an opening in a bracket 23 formed integrally with casing 11.

The impulsing shaft carries a worm gear which meshes with worm gear of the usual speed governor. One end of the speed governor shaft is journaled in a bearing which is supported by a tab 35 integrally formed with the bracket 23 and the casing 11, while the other end of the governor shaft is supported in a bearing in a tab 21 which is also integrally formed with casing 11.

Also formed integrally with casing 11 is the structure 22 upon which are mounted the usual shunt and impulsing spring contacts of the calling device.

In view of the foregoing description of the construction and arrangement of casing 11, it will be understood that the bracket 23, the tabs 21 and 35 and the structure 22 are formed integrally therewith incident to the die casting operation and that the necessary openings for the pins 18, screws 19, the counter recesses for nuts 20, as well as the openings for the respective shafts are all formed during the die-casting operation so that no subsequent machine operations are required to complete the casing 11.

Referring now more particularly to Figs. 3 to 6, inclusive, the manner in which the casing 11 is firmly clamped between two hard metal pieces will be explained in detail. The number plate retaining spring 27 is placed in the cup portion of the casing and the driving spring tension plate 24 is placed on the outside of casing 11 with the lugs 30 and 31 extending through holes provided in the casing 11 and the number plate spring 27 after which the lugs 30 and 31 are bent over in the position shown to assemble these members together. The portion 44 of hub 40 is then forced-fit into the shoulder 32 of the driving spring tension plate 24 until the shoulder 41 abuts against the number plate spring 27 after which the portion 42 of the hub 40 is ring-staked, as shown in Fig. 5, to form a ring 43 around the shoulder 32 to securely clamp the hub 40, spring 27, casing 11, and plate 24 together. The plate 24 is made from cold rolled steel and the spring 27 from sheet steel thereby forming

two hard metals for clamping the relatively soft cast zinc alloy casing 11 without danger of breakage, either during the staking operation or during subsequent use.

The operation of the calling device 10 is the same as that described for the previously mentioned Obergfell patent and need not therefore be described in detail. The finger of the user is first inserted into one of the holes 14 after which the finger hole dial is rotated in a counter-clockwise direction until the finger engages the finger stop 16 after which, when the finger is removed, the dial returns to normal. During the initial measured movement of the dial the extensions in the member 33 permit the closure of the shunt spring contacts and the movement of the impulse spring contacts to a position preparatory to operation by the impulse cam 34. During the return to normal, the impulse cam is rotated under control of the tensioned drive spring 25 and speed governor to separate the impulse spring contacts a number of times corresponding to the digit dialled. When the operating shaft reaches its normal position the member 33 separates the shunt spring contacts and moves the impulse spring contacts out of range of the impulse cam.

The various features and advantages of the invention having been described and ascertained, what is considered new and is desired to have protected by Letters Patent will be pointed out in the following claims.

What is claimed is:

1. In an impulse sending device, a die-cast casing, a number plate, a number plate spring having bent over ends for holding said number plate on said casing, a driving spring for transmitting motion, a driving spring tension plate having lugs for holding said driving spring, ears on said driving spring tension plate extending through holes in said casing and said number plate spring for assembling said number plate spring, said casing and said driving spring tension plate; a hub extending through a hole in said number plate spring, a hole in said casing and a hole in said driving spring tension plate; said driving spring tension plate being force-fit on said hub, a shoulder on said hub abutting against said number plate spring, and a ring-stake pressed from said hub against said driving spring tension plate to firmly clamp said casing between said spring tension plate and said number plate spring.

2. In an impulse sending device, a die-cast casing of relatively soft zinc alloy, openings and mounting means integrally formed with said casing during the casting operation to form a complete structure ready for assembly, a number plate, a number plate spring of relatively hard metal for holding said number plate in place on said casing, a driving spring for transmitting motion, a driving spring tension plate of relatively hard metal having lugs for holding said driving spring, a hub extending through the openings in said number plate spring and said casing and forced-fit through an opening in said driving spring tension plate, and a ring-stake pressed from said hub against said driving spring tension plate to firmly clamp said casing between said driving spring tension plate and said number plate spring.

3. A calling device of the impulse transmitting type comprising a die-cast casing having a substantially cup-shaped configuration, a number plate, a number plate spring for holding the

number plate in place on said casing, a driving spring for transmitting motion, a driving spring tension plate having lugs for holding said driving spring; a hub extending through a hole in said number plate spring, a hole in said casing and a hole in said driving spring tension plate; said driving spring tension plate being forced-fit on said hub, a shoulder on said hub abutting against said number plate spring, and a ring-stake pressed from said hub against said driving spring tension plate to firmly clamp said casing between said spring tension plate and said number plate spring.

4. In an impulse sending device, a die-cast casing, an impulse shaft, an operating shaft, a bracket cast-formed integrally with said casing for mounting said impulse shaft, a speed governor for controlling the rotation speed of said impulse shaft, tabs cast-formed integrally with said bracket and casing for mounting said speed governor, impulsing spring contacts and cam spring contacts, means cast-formed integrally with said casing for mounting said impulse spring contacts and said shunt spring contacts, a number plate, a number plate spring having bent-over ends for holding said number plate on said casing, a driving spring for transmitting motion to said operating shaft, a driving spring tension plate having lugs for holding said driving spring, ears on said driving spring tension plate extending through holes in said casing and holes in said number plate spring for assembling said number plate spring, said casing and said driving spring tension plate; a hub for mounting said operating shaft, said hub extending through a hole in said number plate spring, a hole in said casing and a hole in said driving spring tension plate; said hub being forced-fit in said driving spring tension plate, a shoulder on said hub abutting against

said number plate spring, and a ring-stake pressed from said hub against said driving spring tension plate to firmly clamp said casing between said driving spring tension plate and said number plate spring.

5. In an impulse sender, a cup-shaped casing, a finger-hole dial plate, a driving shaft, means including said shaft for rotatably mounting said dial plate on said casing, a number plate, a number plate retaining spring for holding said number plate on said casing below said dial plate, a driving spring for rotating said dial plate, a driving spring tension plate for holding said driving spring, means for assembling said casing between said number plate retaining spring and said driving spring tension plate, a hub for said shaft extending through an opening in said number plate retaining spring, through an opening in said casing and forced-fit into an opening in said driving spring tension plate, and a ring-stake pressed from said hub against said driving spring tension plate to securely clamp said casing between said driving spring tension plate and said number plate retaining spring.
